UNITED STATES PATENT OFFICE.

HOWARD BUTT, OF WORCESTER, MASSACHUSETTS, ASSIGNOR TO RILEY STOKER CORPORATION, OF WORCESTER, MASSACHUSETTS, A CORPORATION OF MASSACHUSETTS.

METALLURGICAL FURNACE.

Application filed March 25, 1925. Serial No. 18,157.

This invention relates to metallurgical furnaces and more particularly to the construction of a metallurgical furnace which has a heating chamber and a fuel combustion furnace associated therewith.

In the metallurgical industry, a melting furnace, such as is used in an iron foundry, has ordinarily been heated by a combustion furnace which is hand-fired and is accordingly intermittent in its operation. A coal burning furnace of simple design having a manually operated dumping grate is usually built in front of the bridge wall of the melting furnace. The fuel is fed through a door in the furnace wall onto a ledge within the furnace where it is permitted to remain for a short time, after which it is pushed onto the burning fuel bed and another charge is placed on the ledge. This is done to produce gas and a consequent long flame which will reach into the melting zone. During the comparatively long time that the door is open for replenishing the fuel, a considerable amount of oxygen is admitted into the furnace, and consequently the bath of melting iron is subjected to the alternating influences of reducing and oxidizing flames. This results in a considerable variation in the oxygen content of the iron and of course has a marked effect on the quality and physical characteristics of the metal produced.

Numerous attempts have been made to employ an automatic fuel feeder with a metallurgical furnace but they have not been heretofore successful. The advantages inherent in stoking such a furnace automatically and continuously are obvious. One important consideration is that the oxygen content of the product will be kept more nearly uniform and the operation of the furnace will be materially simplified and less manual labor will be required to control the furnace.

It is accordingly one object of my invention to secure these advantages and to provide a metallurgical furnace into which the fuel may be fed automatically and which will be highly efficient in its operation and produce a substantially uniform product.

A further object is to provide a metallurgical furnace with a self heated gas producer which is so constructed and arranged that it will produce a large amount of combustible gas at a uniform rate and will maintain a reducing flame for the proper heat treatment of material in the heating chamber.

With these and other objects in view as will be apparent to one skilled in the art, my invention resides in the combination of parts set forth in the specification and covered by the claims appended hereto.

In accordance with my experimentations, I have discovered that a metallurgical furnace having a heating chamber separated from a combustion furnace by a bridge wall should involve certain well-defined principles of construction. The combustion furnace should be so constructed that the fuel will not be burned completely therein, but gases will be distilled from the coal to a large extent. These should be passed over the bridge wall to the heating chamber and burned there as a long flame closely adjacent to the material to be treated. In order to produce a reducing gas in a self contained automatically operated furnace, I find that the furnace should be so constructed and operated that the heat of combustion of the fuel itself will be largely expended in producing gas from the green coal and that fresh fuel should be continually introduced into the furnace and fed progressively towards an ash dump. Moreover the gas producing furnace should be so constructed and arranged that the gas will not have an opportunity to burn over the fuel bed but must pass into the heating chamber where its radiant heat will be directly available. To this end, I preferably introduce the coal into the combustion furnace at a point near the passage through which the combustible gases enter the heating zone. The fuel is fed progressively into an underfeed retort in the furnace, to form a deep bed from which the volatile matter may be distilled, and is gradually moved laterally on to a support towards an ash discharge. Air is introduced to the interior of the fuel bed on the support to cause combustion and furnish heat for distilling volatile products from the fuel in the retort.

A further limited amount of air is supplied to the retort to aid in the production of combustible gas. The furnace walls are so constructed and arranged that heat from the burning fuel is reflected onto the green fuel in the retort, and insufficient space is provided over the fuel for the gases to burn there so that they must pass over the bridge wall into the heating chamber for combustion. Furthermore, the excess of air fed to the fuel on the lateral support is mixed with the pro-

ducer gases by the time they reach the heating chamber so that the flame is of substantially uniform character.

One simple embodiment of this invention 5 applicable for melting metals comprises a deep fuel retort located close to and parallel with the front bridge wall of the melting hearth. The fuel is fed automatically through a side wall of the furnace into this 10 retort and is caused to move gradually away from the bridge wall over an extension fuel support arranged laterally of the retort which terminates with an ash discharge. I prefer 15 a construction in which the extension support comprises branch retorts opening into and extending laterally of the main retort and towards the front of the furnace, the far ends of the branch retorts connecting with the ash discharge. Air is fed under suitable 20 pressure through tuyères so located that the major portion of the combustion takes place preferably at points remote from the main retort and the heat is transmitted thereto to distill gas from the fuel. For this 25 purpose I may employ tuyères between the branch retorts or otherwise suitably located. I prefer also to have the furnace roof slope forwardly so as to reflect heat onto the entering fuel, and the roof is located comparatively 30 close to the fuel bed so as to limit materially the combustion space over the fuel.

Referring to the drawings illustrating one embodiment of the invention, and in which like reference numerals indicate like parts:

35 Fig. 1 is a vertical elevation of my metallurgical furnace taken on the line 1—1 of Fig. 2;

Fig. 2 is a horizontal section on the line 2—2 of Fig. 1;

40 Fig. 3 is a vertical section on the line 3—3 of Fig. 1;

Fig. 4. is an enlarged detail view showing a vertical side elevation partly broken away of the gas producing combustion furnace;

45 Fig. 5 is a perspective view partly broken away looking lengthwise of the furnace; and

Fig. 6 is an enlarged fragmentary vertical section of a tuyère block and the adjacent retort sides.

50 Referring particularly to the drawings, I have there shown a melting furnace comprising a hearth 10, side walls 11, and a roof 12 thereover which is ordinarily formed of bungs 13 or separate arch structures capable of being removed for introduction of material into the melting zone. A bridge wall 14 is located at the front end of the hearth and a second wall 15 near the rear end, space being provided over the two end walls and beneath the roof to form a suitable passage for the gases and products of combustion. The passage over the rear wall connects with a flue 16 opening into the stack. It will be understood that the construction of the hearth and associated furnace parts may be in ac-

cordance with any approved plan as is well understood by those skilled in the metallurgical art, and detailed description thereof is not necessary for a complete understanding of my invention.

70 The fuel combustion and gas producing furnace is located in advance of the opening over the bridge wall 14, and in order that there may be no loss of heat I prefer that this bridge wall form the rear wall of the combustion furnace. For the purpose of producing combustible gas rapidly and in large quantity, I preferably provide a furnace construction which has a deep retort 18 in front of the bridge wall 14 and a suitable number 75 of branch retorts 19 opening into the main 80 retort.

85 The main retort comprises a rear wall plate 20 surmounted by tuyère plates 21 extending from one side wall 11 of the furnace to the other parallel with the bridge wall. The front wall of this retort is made up by the spaced rear walls 22 of the tuyères between the branch retorts which are so shaped and located that the branch retorts merge into the 90 main retort. The effective bottom of the main retort is a sliding plate 23 located over the bottom plate 24 supported on suitably arranged I-beams 25 carried by the bridge wall 14 and a partition 28. The branch retorts are made of U-shaped castings having bottoms 26 which are continuations of the bottom plate 24. The branch retort bottoms 26 are horizontal at their rear ends but slope upwardly towards the front of the furnace 95 and join with horizontal plates 27 extending across the furnace. The front ends of the branch retorts are so shaped that they may be suitably supported by a transverse I-beam 29 which is in turn supported by the 100 longitudinal I-beams 25.

105 As will be apparent by inspection of Fig. 6, the side walls 30 of the adjacent branch retorts are spaced apart and form hollow air spaces beneath. The tops of these walls 110 are surmounted by hollow tuyère blocks 31 having air openings 32 therethrough communicating with the wind box 33 beneath the retorts which is separated from the ash pit 35 by the partition 28. The plates 27 may have tuyère openings 34 therethrough and all of the various tuyères will be in communication with the wind box. Air under pressure is admitted to the wind box through an inlet pipe 36 connected with a blower, and the pressure of the air may be suitably regulated by dampers and other devices.

115 Ash dump plates 37 are hinged to a ribbed support carried on an upright plate 38 on the top of the wall 28, and they are so constructed and arranged that they will normally remain in a horizontal position and support the fuel bed thereover, but may be 120 swung downwardly by suitable mechanism to dump the material into the ash pit. These 125 130

plates have tuyère openings 39 therethrough, and air may be admitted from the wind box thereto through a slide valve 40 in the partition plate 38, which may be suitably adjusted by a rod connected thereto and passing to a point outside the furnace walls.

In order to move fuel progressively into the main retort and thence into the lateral retort, I provide a suitable mechanism which 10 may comprise a ram 40 arranged to feed coal from a hopper 41 on the side of the furnace through a throat 42 into the lower portion of the main retort. This ram may be reciprocated by any suitable means such as a steam 15 engine. The sliding plate 23 is connected with the ram and arranged to reciprocate therewith. Mounted on this plate are pusher blocks 45, which preferably have vertical front walls and rearwardly sloping tops so 20 arranged that they not only cooperate with the ram to feed the fuel forward through the main retort, but they tend to lift the fuel bed as they move backwards, thus keeping the coal bed loose and preventing the formation 25 of large coke masses.

As a suitable means for moving the coal laterally into the branch retorts, I preferably provide pusher blocks which are arranged one in each branch retort and are so connected to operating mechanism that they will reciprocate in alternate directions at the same time, thereby tending not only to move the fuel laterally into these branches but to slice the fuel bed along lines between adjacent retorts. These branch pusher blocks 50 and 51, as shown particularly in Fig. 4, may have flat bottoms adapted to slide on the horizontal portion of the floor 26 and tops so shaped that they will slide beneath the plate 23. A wedge-shaped nose 52 is preferably provided so that the coal as it is moved forward will be given a lifting motion. These lateral pusher blocks may be reciprocated by any suitable mechanism such as cranks 53 and 54 operated by a steam engine connection. The cranks are connected by the links 55 and 56 with lugs projecting from the bottoms of the pusher blocks through slots in the floor 26. The pusher blocks 50 and 51 are also provided with rollers 57 which contact with the underside of the bottom plate 24 and thereby keep the pusher blocks from being lifted from contact with the horizontal portion of the floor 26 by an accumulation of coal therebetween.

It will be noted by inspection of Fig. 1 that the roof over the gas producer and combustion furnace has been made to slope downwardly toward the front of the furnace so as to provide a very small space over the fuel bed for the volatile gases. Their rate of travel is so regulated that although they are mixed with air for complete combustion, there will be no opportunity for a large amount of the gas to burn over the fuel bed

but it must pass over the bridge wall and burn over the melting hearth. That is, the furnace is essentially a gas producer, and only so much fuel should be burned therein as is necessary for an efficient production of combustible gas.

The sloping wall of this roof has another function. The green fuel is fed into the main retort to form such a deep bed that it cannot readily burn except adjacent the top layer 70 near the tuyère openings, hence it is necessary that heat be introduced into this large mass of coal so as to distill the volatile matter therefrom. The upwardly sloping retort bottoms 26 and the downwardly sloping tops 80 of the tuyère blocks 31 are so arranged that the fuel bed gradually decreases in thickness from the rear of the furnace towards the dump plates. The tuyère openings, as may be seen in Fig. 4, gradually approach the 85 bottom of the fuel bed towards the front of the retorts, hence the combustion of the fuel becomes more pronounced towards the dump plate. In order to use efficiently the heat thus generated, I slope the roof so that it will reflect this heat down onto the deeper portions 90 of the fuel bed, thereby serving to raise the temperature therein to a material extent.

It will be observed that the tuyère plates 21 are so constructed that air is admitted into the main retort only through openings 60 at the lower ends of the plates, so that there is little opportunity for the fuel in this retort to burn. I may in some cases omit all or a larger part of these tuyère openings. Similarly, the upper portions of the tuyère blocks 61 which form the tops of the outer walls of the two end lateral retorts are left blank and air is admitted to a limited extent through the openings therein located on a level with the 105 tuyère openings 32. These blocks and the blocks 21 are arranged to project above the tops of the tuyère blocks 31 so as to hold the fire away from the side walls of the furnace; but, as illustrated, the air inlet openings are 110 preferably few in number and small in size so as to minimize combustion but insure proper cooling of the plates. In other words, I provide such a construction and I so operate the furnace that the coal is burned only sufficiently to provide the necessary heat for producing a combustible gas. It will be obvious that various changes may be made in the tuyère and retort structures in order to admit air into such portions of the furnace as seems most desirable to obtain the maximum efficiency, provided the furnace is so operated to make it substantially a gas producer.

In operating the furnace, coal is fed from the hopper 41 into and along the main retort 125 and then into the branch retorts by the pusher blocks. The coal is fed at such a rate that it piles up into a high bed of coal over the tops of the tuyères. Sufficient air under suitable pressure is admitted to form a hot flame at the 130

front end of the furnace. The heat from this flame is transmitted to the fuel in the retort and aids in distilling volatile products therefrom. The limited amount of air admitted 5 to the fuel in the retort causes incomplete combustion and the formation of combustible gases, and these rich gases rise and pass over the bridge wall before they are burned. Owing to the shape of the furnace walls and the 10 constricted throat over the bridge wall, the excess of air supplied in the branch retorts and the volatile gases produced in the main retort are thoroughly mingled by the time they have reached the heating chamber. In 15 order that the flame caused by these gases may impinge on the metal bath, I prefer to provide a dip in the roof adjacent the opening over the bridge wall 14 which will cause the gases to shoot downwardly towards the 20 hearth. This may be effected by so constructing and arranging the bungs 65 that they form an angle in the roof as illustrated in Fig. 1. Beyond this constricted portion a larger amount of space is provided so that the burning 25 gases may have room to expand. When it is desired to run a heat and melt a charge of iron, the gas producing furnace is started into operation and run continuously during the entire time that the iron is to be melted. 30 When the process is completed, the furnace is raked out and the coke removed therefrom so that another batch of iron may be subjected to the reducing gases generated from a fresh body of fuel. The quantity of air introduced 35 into the gas producer is varied in order to give the desired conditions in the furnace, and this is ordinarily so carried on that the flame is highly reducing and that the iron on the hearth is not subjected at any time to an 40 oxidizing atmosphere as occurs when the furnace is operated intermittently. Although the fuel is fed into the furnace by an intermittent action, this movement is such that the production of gas is a continuous one and the 45 variation in quality and quantity of the gas passing into the melting furnace will be very slight during an entire run, hence it is possible to keep the oxygen content of the iron quite uniform. The temperature of the furnace 50 may be stabilized and a higher temperature produced than can be obtained with a hand-fired furnace for a given amount of fuel, or less fuel is required to obtain a given heat treatment, owing to the fact that there is a 55 considerable amount of cold air introduced in the latter type of furnace every time the fuel-feeding door is opened. By introducing the coal laterally through the side wall of the furnace, it is possible to get the fresh green coal close to the bridge wall and the 60 opening thereover so that the gases passing upwardly from the main retort will flow over the bridge wall without having to pass over the hot fuel bed and in contact with air which is coming upwardly therethrough. The air 65 which is introduced through the tuyères between the branch retorts will flow upwardly and mingle with the gases from the main retort in the throat over the bridge wall and as they enter the melting furnace. It will also 70 be noted that I do not need to introduce air through the bungs for burning the gases, as has heretofore been done, but that sufficient air may be introduced in the gas producer and caused to mix thoroughly with the gases 75 before and as they pass over the bridge wall. This prevents any danger of localized oxidation of the bath, as is often caused when jets of cold air are blown through the bungs into 80 the furnace. 85 It will be obvious that various changes may be made in the construction of this furnace within the scope of my invention as set forth in the claim appended hereto, and that a metallurgical furnace of the type herein described is applicable to numerous heating operations required in this art. 90 Having thus described my invention, what I claim as new and desire to secure by Letters Patent is: 95 A metallurgical furnace comprising walls defining a heating chamber, and a combustion chamber connected by a narrow restricted passage over a bridge wall, an underfeet retort in the combustion chamber substantially 100 parallel with and adjacent to the bridge wall, a fuel support laterally of the retort and arranged to receive fuel therefrom, means to feed fuel progressively to the retort and on to the support, means to feed air through the fuel bed on the support to cause combustion, and means to supply a limited amount of air to the fuel in the retort, whereby combustible gas is produced in large quantity, the roof of the furnace being located close to the fuel bed to restrict combustion thereover, and sloping to reflect heat from the burning fuel on the support to the fuel in the retort, and having a deflecting portion so arranged that the air and combustible material are projected towards the bottom of the heating chamber as they enter the latter and they are caused to mix thoroughly and burn as a long flame. 105 110 Signed at Worcester, Massachusetts, this 23rd day of March, 1925.

HOWARD BUTT.
